UNITED STATES PATENT OFFICE.

PAUL STAMPKA, OF NAMPA, IDAHO, ASSIGNOR OF ONE-TENTH TO OGDEN DUTCHER,
ONE-TWENTIETH TO WILLIAM P. O'CONNOR, AND ONE-TWENTIETH TO AUSFRID
L. ANDERSON, ALL OF NAMPA, IDAHO.

PRIMING DEVICE FOR GASOLENE-ENGINES.

1,267,007.

Specification of Letters Patent. Patented May 21, 1918.

Application filed November 14, 1917. Serial No. 201,968.

To all whom it may concern:

Be it known that I, PAUL STAMPKA, a citizen of the United States, residing at Nampa, in the county of Canyon and State of Idaho, have invented certain new and useful Improvements in Priming Devices for Gasolene-Engines, of which the following is a specification, reference being had to the accompanying drawings.

10 This invention relates to an improved priming device for gasolene engines employed for the production of motive power in connection with various classes of vehicles, such for instance, as automobiles, aeroplanes and the like.

15 It is a primary object of the invention to provide simple and effective means under the instant control of the operator for supplying a priming charge of the motive fuel in a finely atomized state directly to the cylinders of the engine.

20 It is another and more particular object of the invention to provide a priming apparatus for the above purpose embodying 25 a pump including a cylinder connected to a pressure receiving tank, a manually operable valve to open communication between the tank and a source of fuel supply or between the tank and the atmosphere, and an additional manually operable valve to control 30 the supply of pressure fluid from the tank to the priming cups of the engine cylinders.

It is another one of the detail objects of 35 the invention to provide an improved construction of the release valve for the priming charge and means for operating said valve from the dash or instrument board of the vehicle.

40 And it is a further general object of the invention to improve and simplify apparatus of the above character, rendering the same highly efficient and positive in its operation, and capable of manufacture at comparatively small cost.

45 With the above and other objects in view, the invention consists in the improved combination and arrangement of the several parts to be hereinafter particularly described and subsequently pointed out in the 50 appended claim.

In the accompanying drawings wherein similar reference characters designate corresponding parts throughout the several views;

Figure 1 is a side elevation disclosing one embodiment of my invention and showing the same mounted upon the vehicle dash;

Fig. 2 is a vertical sectional view through one end of the pump cylinder illustrating the valved connections to the pressure tank 60 and the gasolene supply;

Fig. 3 is an enlarged sectional view through the release valve taken on the line 3—3 of Fig. 1; and

Fig. 4 is a face view of the key plate 65 mounted on the vehicle dash or instrument board.

Referring in detail to the drawing 5 designates a pump cylinder which, in the illustrated construction, is connected to a flange 70 or boss 6 projecting from one face of the key plate 7 which is secured upon the tank or instrument board D with which the vehicle is equipped. To the other end of this cylinder, a hollow head 8 is detachably connected by means of a threaded coupling sleeve 9. This head is provided at diametrically opposite points with nipples 10 and 11 respectively. The nipple 11 is provided with a valve seat 12 upon which the valve ball 13 is normally engaged. A sleeve or bushing 14 has threaded engagement in the nipple and limits the movement of the valve ball 13 from its seat. This nipple is connected by the pipe 14 to a pressure receiving tank (not shown), mounted at any convenient point upon the vehicle body.

A bushing 16 is likewise threaded in the nipple 10 and has a seat 17 formed on one end to receive the valve ball 18. The displacement of said ball from its seat is limited by the shoulder 19 formed in the bore of the nipple. To the nipple 10 a valve casing 20 is connected, and in the casing a rotatable valve plug 21 is engaged. This 95 plug is formed with a transverse port 22 and an orifice 23 extending at right angles to this port communicates with one side of the port and opens upon the periphery of the valve plug. The casing 20 is provided with a longitudinally extending passage 24 in communication with the bore of the nipple 10. Gasolene is delivered from a suitable supply tank to the other end of this passage through the medium of a pipe or tube 25 which is 100 connected to the casing 20 by means of a coupling sleeve 26. The casing 20 is additionally provided with a transverse port or

- orifice 27 which is open to the atmosphere. It will thus be readily understood from reference to Fig. 2 of the drawing that in one position of the valve plug 21, the port 22 thereof is in alinement with the passage 24 whereby gasoline will be supplied to the cylinder 5 in the operation of the pump. By turning the plug 21 through 90 degrees, the orifice 27 in the valve casing is connected to the passage 24 through the medium of the port 22 and orifice 23 of the valve plug. Thus the gasoline supply is cut off and in the continued operation of the pump, air is drawn into the pump cylinder.
- 15 The valve 21 may be conveniently operated by means of a rod 27' operatively connected at one of its ends to the valve member and having its other end extending through the dash D and rotatably mounted in the key plate 7, a suitable head or finger piece indicated at 28 being fixed to the latter end of the rod.

15 The piston 29 which reciprocates in the pump cylinder 5 is operated through the medium of a rod 30 which extends through the head on the end of the cylinder mounted in the key plate 7 and is equipped with a suitable hand hold indicated at 31. It will of course, be readily seen that in the movement of the piston 29 in one direction, either gasoline or air is drawn into the cylinder past the valve 18, in accordance with the adjustment of the valve plug 21 and in the movement of the pump piston in the opposite direction, the fluid is forced under pressure from the cylinder through the pipe connection 15 to the pressure receiving tank.

15 The cylinder head 8 is formed on its end face with a T-shaped enlargement or projection 32, the vertical portion of which is longitudinally bored as at 33 and provided at its lower end with a threaded nipple 34 for the connection thereto of the pipe or tube 35. When the engine is provided with 45 a double row of cylinders, a T-coupling may be provided for the connection of tubes 35 to the bore 33. The horizontally disposed portion of the enlargement 32 on the cylinder head has a bore 36 in one end thereof to 50 which the pipe 37 extending from the pressure receiving tank is suitably connected. At the other end of this bore 36, a valve 40 has threaded engagement as at 41 in the opposite end of the horizontal arm of the enlargement 32. A threaded opening is provided above the needle valve and in alinement with the bore 33, said opening being normally closed by means of a plug 42. This opening is provided for permitting 55 convenient access to the bore or passage and the valve seat 38 for the purpose of cleaning the tank.

15 To the outer end of the needle valve rod 40, a downwardly extending curved arm 43 is fixed. This arm is recessed in concentric

relation to the valve rod to receive one end of the coil spring 44 loosely surrounding said rod, the said end of the spring being fixed to the valve rod. The other end of the spring is secured to a pin indicated at 45 projecting from the cylinder head 8. The arm 43 is actuated by means of a rod 46 connected to the other end of said arm and extending in parallel relation to the pump cylinder 5 through the dash board and the key plate 7, said rod being provided on the latter end thereof with a finger button or head 47. Normally, the spring 44 acts to hold the valve rod against turning movement with the needle point 39 of said rod 80 engaged upon the seat 38, thus closing communication between the vertical bore or passage 33 and the pressure tank. When it is desired to open this valve to release a priming charge into the pipe or tube 35; the button 47 is pressed to force the rod 46 longitudinally, and thereby swing the arm 43 to rotate the needle valve 40 against the action of the spring 44. In this rotation of the valve rod, owing to its threaded connection 90 with the part 32, said valve rod will shift longitudinally and the needle point 39 thus be moved away from the seat 38. The air pressure in the pressure tank, acting upon the gasoline, breaks the same up into minute 95 particles and immediately upon the opening of the needle valve, this atomized gasoline is forced under pressure through the passage 33 and into the pipe or tube 35.

15 In the accompanying drawing, I have 100 illustrated a coupling 48 adapted to connect a goose-neck pipe 49, which is suitably connected to the pipe or tube 35 to the priming cup of one of the engine cylinders. It will of course, be understood 105 that one of these couplings is provided between each engine cylinder and the pipe 35. Each coupling 48 preferably includes a spring pressed valve rod or pin indicated at 50 which normally closes communication 110 between the priming cup and the pipe or tube 35, said rod being engaged at its lower end upon the valve seat indicated at 50'. This valve rod may be of any suitable form and construction, but as illustrated it is of 115 slightly less diameter than the coupling member connected to the priming cup through which said rod extends, so that the fuel will be delivered in radial directions in 120 its atomized condition into the priming cup and thence to the engine cylinder.

15 From the foregoing description taken in connection with the accompanying drawing the construction, manner of operation and several advantages of my invention will be 125 clearly and fully understood. The valve 21 is first adjusted so that upon the operation of the pump piston, gasoline will be supplied to the pressure tank, and by then turning the valve 21 as indicated, air is drawn into 130

the pump cylinder and forced into the pressure tank where it impinges upon the gasoline and breaks the same up into a spray. One operation of the pump in this manner 5 is sufficient to supply the tank with several priming charges for the engine cylinders. Upon now operating the needle release valve 40, the priming charge of atomized gasoline is immediately supplied directly to the 10 engine cylinders so that the engine may be immediately started, even in severely cold weather. By means of my improved priming apparatus, all danger of overcharging or flooding the engine cylinders, as is frequently 15 the case when the carburetor is flooded, will be obviated. As the pump and the several valves are operable from the dash or instrument board of the vehicle, the operator is not required to leave his 20 position and he may at any time ascertain, by the operation of the primer whether or not the carburetor is in good working condition.

The invention as herein described, 25 consists of relatively few parts which are of simple form and construction so that the entire apparatus may be produced at relatively small manufacturing cost and installed upon automobiles, aeroplanes and other motor driven vehicles without necessitating any 30 material structural alterations in the vehicle. The foregoing disclosure has relation to one embodiment of the invention which I have found to give very satisfactory results 35 in practical use, but it is to be understood that in the adaptation of the priming apparatus to various types of vehicles, certain

mechanical alterations may be required. Therefore, while I have herein shown and described a certain form, construction and 40 arrangements of the various elements, the same are nevertheless susceptible of considerable modification, and I accordingly reserve the privilege of adopting all legitimate changes which may fairly be considered within the spirit and scope of the invention as claimed.

I claim:

In a priming apparatus for internal combustion engines, a pump including a cylinder and piston operating therein, said cylinder having a head on one end, a connection between said cylinder head and a pressure receiving tank, a manually operable valve connected to said head to open communication either between the cylinder and a source of fuel supply or between the cylinder and the atmosphere, said cylinder head being additionally provided with a passage, a supply connection leading from the pressure 60 tank to said passage, a valve normally closing communication between said supply connection and the passage, a conduit connecting said passage to the several engine cylinders, and manually operable means connected to the valve to open the same and release a priming charge into said conduit.

In testimony whereof I hereunto affix my signature in the presence of two witnesses.

PAUL STAMPKA.
